The ornamental design for the power adapter for monitor-defibrillator, as shown and described.

DESCRIPTION

FIG. 1 is a top, side, and end perspective view of a first embodiment of a power adapter for monitor-defibrillator showing my new design;

FIG. 2 is another perspective view thereof, showing the opposite end of that in FIG. 1;

FIG. 3 is a top plan view thereof;

FIG. 4 is a bottom plan view thereof;

FIG. 5 is a first side elevation view thereof;

FIG. 6 is a second side elevation view thereof;

FIG. 7 is a first end elevation view thereof;

FIG. 8 is a second end elevation view thereof, opposite that of FIG. 7;

FIG. 9 is a top, side, and end perspective view of a second embodiment of a power adapter for monitor-defibrillator showing my new design;

FIG. 10 is another perspective view thereof, showing the opposite end of that in FIG. 9;

FIG. 11 is a top plan view thereof;

FIG. 12 is a bottom plan view thereof;

FIG. 13 is a first side elevation view thereof;

FIG. 14 is a second side elevation view thereof;

FIG. 15 is a first end elevation view thereof;

FIG. 16 is a second end elevation view thereof, opposite that of FIG. 15;

FIG. 17 is a front elevation view of embodiment 1 shown in environmental use; and,

FIG. 18 is a perspective view of embodiment 1 shown in environmental use.

The broken lines shown represent unclaimed subject matter only and form no part of the claim. Where broken lines abut a claimed surface it is understood that those broken lines represent an unclaimed boundary between claimed and unclaimed surfaces. None of the broken lines form any part of the claimed design.
